ART OF DISPENSING GREASE

Filed March 21, 1927

Fig. 2

WITNESS

Robt. Woolsey

UNITED STATES PATENT OFFICE.

THEODORE EDWARD BAKER, OF LOS ANGELES, CALIFORNIA, ASSIGNOR, BY MESNE ASSIGNMENTS, TO ALEMITE MANUFACTURING CORPORATION, OF CHICAGO, ILLINOIS, A CORPORATION OF DELAWARE.

ART OF DISPENSING GREASE.

Application filed March 21, 1927. Serial No. 176,985.

This invention includes the method of and means for dispensing grease of different consistencies and an object of the invention is to dispense the two characters of grease by 5 a single charge of compressed air; and the invention broadly includes maintaining two fluid bodies under pressure, the pressure upon one of the bodies being effected by a compressed fluid and the pressure upon the other body being applied by fluid pressure of the first body, and discharging, controlling and stopping the discharge from the said bodies independently of each other, alternately or simultaneously.

15 In carrying out this invention, I provide two containers each having a valved outlet and adapted to contain fluid under pressure; one of said containers being in the form of a cylinder; a free piston in the cylinder; an 20 inlet to said cylinder on one side of the piston and a valve controlled outlet from said cylinder on the other side of the piston; and means to apply fluid pressure to the contents of the first container, thereby to express the contents of said containers toward the outlets or either of them when the same are open respectively; that is to say, in this invention the compressed air upon the contents of the first 25 container is applied through such contents and the free piston to force the contents out of the second container when the outlet from said container is open.

30 Heretofore greases, lubricants and other commercial liquids were handled and dispensed from separate and distinct containers for each grade or character of liquid and each container was accompanied with its individual pressure chamber, pressure gage and valve controlled intake for the pressure fluid and 35 with its carrying and transporting means.

40 In this invention I construct in a single apparatus a plurality of separate and distinct liquid dispensers and a single pressure chamber, gage and intake therefor, which is common to the several dispensers, to the end that a single dispensing unit may selectively serve liquids of different characters.

45 According to former, or the methods in vogue, such jobs as, for example, the lubrication of an automobile, wherein a heavy oil, or grease, is desired for gear lubrication and a lighter oil desired for the crank case, the operator was required to charge separate containers with compressed air, and to separately

carry, or otherwise transport them to the 55 automobile.

An object of my invention is to provide a liquid dispensing apparatus constructed as a unit and which comprises distinct liquid containers, a controllable outlet for each container and a single pressure means for the several containers, whereby the control of the pressure means is facilitated and the transporting of and dispensing from the several containers is accomplished with a minimum 60 of effort.

A further object is to provide a method of dispensing fluids which consists in separately confining two, or more, bodies of fluid, and in utilizing an internal pressure of one of the 70 bodies in the delivery of the other body, or bodies.

A further object is to provide a method of dispensing fluids which consists in confining two, or more, bodies of fluid in distinct containers separated by a movable container element; in subjecting one of the containers to an internal pressure and in transferring such pressure through said movable container element to the other container and in utilizing 75 such pressure in the withdrawal of fluids 80 from both or all of the containers.

Still other objects of this invention are simplicity of apparatus and convenience of operation and enabling either one or two operators to work at the same time with one 85 portable device.

Another object of the invention is to provide for maintaining the fluids to be dispensed in a sufficiently fluid state to enable the device 90 to operate upon liquids, such as grease, as may be viscid, stable or stubborn when subjected to relatively low temperature.

Other objects, advantages and features of my invention may appear from the accompanying drawing, the subjoined detailed description and the appended claims.

The accompanying drawing illustrates the invention.

Figure 1 is a vertical sectional elevation 100 of an apparatus constructed in accordance with my invention.

Fig. 2 is a fragmentary elevation showing the relative arrangement of the suspension means for the inner container, air intake and 105 gage and the bale or handle for the outer container.

The container 1, which constitutes the body

of the apparatus, is constructed as a sheet metal cylinder, or drum, having a bottom 2 and head 3. For convenience to its portability, I prefer to provide a wheeled carriage 5 and a handle or bale. The form of carriage shown comprises a body 4, shaped to surround the container 1, as shown in Fig. 1; supports 5 projecting laterally therefrom and a wheel, or wheels 6 whose axle 7 is mounted in said 10 supports.

The recited bale, by preference and as shown, comprises a bar 8 and arms 9, constructed of a single length of metallic rod and of U shape, its arms being secured to 15 the container 1, adjacent its upper end as by means, not shown, such as rivets, or welding. At each end of each arm 9 of the bale there is formed a hook 10 serving as racks for a dispensing hose and dispensing valve 20 hereinafter referred to.

The container 1 serves to hold a body A of liquid, such as a relatively light oil, which only partially fills the container, the remaining space B being utilized as a pressure chamber, and to this end there is provided in the 25 head 3, of the container a valved intake 11 for compressed air and a pressure gage.

Adjacent the bottom of the container is an outlet 12 for the liquid content of the 30 container, to which is secured a section of hose 13, which carries at its free end a nozzle 14 having a flow control valve 15, which may be of any conventional construction.

The hose and its dispensing valve, when 35 not in use may for convenience be hung upon the referred hooks 10 of the bale. In order to determine, or measure the delivered quantities of liquid, a meter, such as is shown at 16 in Fig. 1 may be incorporated in the 40 dispensing line.

Formed through the head 3 is a hole 17, providing for the introduction of a container 18, bodily, into the container 1, which container 18 serves to hold a body C of liquid, 45 such as heavy oil, or grease. The container 18 is by preference suspended from the head 3 of the container 1, and to this end therefore I secure to the head 3, surrounding the hole 17, a relatively heavy metallic ring 19 over 50 and to which I mount and secure as by cap screws 20, a cap or head 21, which includes a filling opening having a screw-plug 22 and a delivery spout 23 to which there is attached a flexible hose 24 carrying at its free end a 55 valve controlling dispensing nozzle 25.

The container 18 is of a length to extend a considerable depth into the body of liquid A in the container 1 and is formed with an open bottom whereby the liquid A may freely 60 move in the lower end thereof. Mounted in the container 18 and for free lengthwise movements therein is a movable container element, preferably, and as shown, constructed as a piston 26, which may be of any conventional construction providing liquid-tight

fit with the inside face of the wall of the container.

In the open bottom of the container I provide a stop for preventing movement of the piston out of the open end which stop is 70 shown as a ring 27, having a down-turned flange 28 and is removably and replaceably held in space by screws 29, extending through the wall of the container. Contributing to the free sliding movement of the piston I employ a piston guide, or aligner 30, which comprises a stem 31 suspended from the piston and a disc which engages the container wall to one side of the piston, which functions to prevent canting of the piston proper. 75

In order to adapt the apparatus to the dispensing of liquids which are not free flowing as by viscosity in low temperature, I provide a heater, which comprises a pocket, or cavity, formed in the container 1 to receive a heat 80 source. By preference the pocket is constructed as a unit 32 formed as by casting, and of cylindrical shape, its inner end being closed and its outer end open, and bears next its open end external screw threads 33, and spaced lugs 34 to receive a lever or bar to effect bodily rotation. Formed in the side wall of the container 1, adjacent its lower end is a hole 35 surrounding which is a reinforcing ring 36, secured as by welding to the 85 outer face of the container and which bears internal threads for engagement with the referred threads of the pocket.

The heat source referred to is by preference an ordinary incandescent electric lamp 100 37, whose socket 38 is secured to a base plate 39 which plate is held, as by screws 40, at the outer open end of the pocket. An ordinary cord 41 and plug 42 provide for connecting the lamp to feed wires, or source, not shown. 105

For the movement of the piston 26 to the bottom of the container 18, upon a dispensing of its content, the liquid body C, I provide a rod, such as 43, which is inserted through the filling opening at the top of container, engaged with the piston for its movement to restore the container to its full capacity. 110

The operation of the apparatus is as follows: assuming the container 1 to be partially filled as by the recited body A of liquid; the remaining space B therein to be charged with compressed air; the container 18 holding the body of liquid C, and the dispensing nozzles 14 and 25 closed. It is obvious that by reason of the movable element of the container 18, the piston 26, the internal pressure in the body A will be directly communicated to the body C and that both separately contained bodies of liquid may be expelled selectively or simultaneously by pressure from a single source. The content of the container 1, being directly expelled by the compressed air and the content of the container 18 being expelled by the pressure of the content of the container 1. 115 120 125 130

A feature of my invention is the construction and relative arrangement of means for holding a number of bodies of liquid physically separated but in a manner to balance, 5 or provide for the intercommunication of internal pressures of, the several bodies of liquid.

Advantages incident to my invention are: 10 lessened cost of production; compactness; simplified charging of a compressible fluid; simplified portability; selective or simultaneous dispensing of fluids of different character from a single dispenser by reason of the operably distinct valve-controlled outlets; 15 adaptation for use by more than one operator and the maintenance of the several liquids in condition for dispensing or ejection.

I claim:

20 1. In a liquid dispensing apparatus, a container; a controllable outlet for a liquid content; means for admitting air under pressure to the liquid content for its expelling; a second container in open communication with the liquid content of the first container; 25 means for admitting a liquid content to the second container; a controllable outlet for

the second container, and a piston in the second container serving to physically separate the liquid contents of the two containers and 30 acting to expel the content of the second container by direct pressure of the content of the first container, the controlled outlets being physically distinct, whereby the contents of the two containers may be selectively or simultaneously operated to deliver either or 35 both liquid contents.

2. In a liquid dispensing apparatus, a container constituting the body of the apparatus and having a filling opening at its upper end; 40 means for admitting compressed air to the container; a controllable outlet for the container; a second container for extension through the filling opening of the first container and having its lower end open for communication with the interior of the first container; a filling opening for the second container; a controllable outlet for the second container, and a piston freely movable within 45 the second container.

In testimony whereof, I have hereunto set my hand at Los Angeles, California, this 16th day of March, 1927.

THEODORE EDWARD BAKER.
